Primary Examiner — Leanne Was-Englehart*Assistant Examiner* — Justin A Johnson(74) *Attorney, Agent, or Firm* — Muncy, Geissler, Olds & Lowe, P.C.**CLAIM**

The ornamental design for a table for optometry, as shown and described.

DESCRIPTION

FIG. 1 is a top, front, and left side perspective view of a table for optometry showing my new design;

FIG. 2 is a bottom, back, and right side perspective view thereof;

FIG. 3 is a front view thereof;

FIG. 4 is a back view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is an enlarged view thereof taken from the broken rectangle in FIG. 5.

The broken lines illustrate enlarged portions of the design. None of the broken lines form part of the claimed design.
